[57] CLAIM

The ornamental design for a bottle, as shown and described.

DESCRIPTION

FIG. 1 is a front elevational view of a bottle showing my new design;

FIG. 2 is a rear elevational view thereof;

FIG. 3 is a side elevational view from the left of FIG. 1;
FIG. 4 is a side elevational view from the right of FIG. 1;

FIG. 5 is a top plan view thereof;

FIG. 6 is a bottom plan view thereof.

The characteristic feature of my new design resides in the general appearance and configuration of the grapes and leaf design on the front.
